US00D916810S

(12) **United States Design Patent** (10) Patent No.: **US D916,810 S**
(45) Date of Patent: **** Apr. 20, 2021**

(54) **DISPLAY SCREEN OR PORTION THEREOF
WITH A GRAPHICAL USER INTERFACE**

8,484,158 B2 7/2013 Deluca et al.

(71) Applicant: **Snap Inc.**, Santa Monica, CA (US)

(72) Inventor: **Matthew Colin Grantham**, Toronto (CA)

(73) Assignee: **Snap Inc.**, Santa Monica, CA (US)

(**) Term: **15 Years**

(21) Appl. No.: **29/692,698**

(22) Filed: **May 28, 2019**

(51) LOC (13) Cl. **14-04**

(52) U.S. Cl.

USPC **D14/486; D14/489; D14/495**

(57) **CLAIM**

The ornamental design for a display screen or portion thereof with a graphical user interface, as shown and described.

DESCRIPTION

The FIGURE is a front view of a display screen or portion thereof with a graphical user interface, showing my new design.

The broken lines showing the device and display screen illustrate environmental structure and portions of the article. The broken lines form no part of the claimed design.

1 Claim, 1 Drawing Sheet
